[57] CLAIM

The ornamental design for a spice rack, as shown and described.

DESCRIPTION

FIG. 1 is a top, front perspective view of a spice rack showing my new design;

FIG. 2 is a top plan view thereof;

FIG. 3 is a right side elevational view thereof, the opposite side being a mirror image;

FIG. 4 is a rear elevational view thereof; and

FIG. 5 is a bottom plan view thereof.

The broken line showing of spice containers in FIG. 3 is for illustrative purposes only and forms no part of the claimed design.
